CLAIM

I claim the ornamental design for a threadless fairlead, as shown and described.

DESCRIPTION

FIG. 1 is a front elevated view of the threadless fairlead showing my new design;

FIG. 2 is a rear elevated view thereof;

FIG. 3 is a top view thereof;

FIG. 4 is a bottom view thereof;

FIG. 5 is a right side elevated view thereof.

FIG. 6 is a left side elevated view thereof;

FIG. 7 is a front left Perspective view thereof; and,

FIG. 8 is a bottom right perspective view thereof.
